CABIN FOR A HELICOPTER

Buford J. Schramm, Tempe, Ariz., assignor to
Rotoway, Inc., Tempe, Ariz.

Filed Mar. 4, 1971, Ser. No. 121,225

Term of patent 14 years

Int. Cl. D12—06

U.S. Cl. D71—1

FIG. 1 is a front perspective view of a cabin for a helicopter, showing my new design;

FIG. 2 is a side elevation of FIG. 1.

The cabin is symmetrical on both sides of its forward centerline. The material shown in dashed lines illustrates a helicopter on which the cabin is used, but forms no part of the invention.

I claim:

The ornamental design for a cabin for a helicopter, as shown and described.
